UNITED STATES PATENT OFFICE.

ARTHUR JAMES TIZLEY, OF BROOKLYN, NEW YORK, ASSIGNOR TO E. F. CALDWELL & CO., OF NEW YORK, N. Y., A CORPORATION OF NEW YORK.

SHADE OR BOWL AND METHOD OF MANUFACTURING THE SAME.

Application filed September 14, 1922. Serial No. 588,201.

To all whom it may concern:

Be it known that I, ARTHUR J. TIZLEY, a citizen of the United States, and a resident of the city of New York, borough of Brooklyn, county of Kings, and State of New York, have invented a new and Improved Shade or Bowl and Method of Manufacturing the Same, of which the following is a full, clear, and exact description.

10 My invention relates to translucent shades or bowls, and a method of manufacturing the same, and it has for its object to provide a shade or bowl which may be used for lamps, in ceiling fixtures, and for other purposes where glass, paper and vellum have been used heretofore.

Another object of the invention is to manufacture a shade or bowl of one or more layers of fibrous material, which are impregnated and stiffened with a filler and which may be subsequently stiffened and thickened by coating the article with another material.

Still another object of the invention is to provide a shade having different gums dissolved in dissimilar substances which are interspersed with fibrous material.

Additional objects of the invention will appear in the following specification, in which the preferred form of my invention is described.

In the drawings, similar reference characters refer to similar parts in all the figures, in which—

Figure 1 is a view showing the form partially in section;

Figure 2 is a view showing the form covered with bees-wax;

Figure 3 is a view partially in section showing the fibrous material stretched over the bees-wax on the form;

Figure 4 is a view showing the fibrous material on the form impregnated with the gum arabic;

Figure 5 is a view showing the fibrous material on the form after the varnish or shellac has been applied;

Figure 6 is a view showing the article after the second layer of fibrous material has been applied;

Figure 7 is an enlarged sectional fragmentary view showing the manner in which the edge of the finished article is stiffened with a wire; and

Figure 8 is an enlarged view showing the finished article.

In the manufacture of the translucent shade or bowl, a form 10 is employed, but it will, of course, be understood that in some cases it may be desired to manufacture a flat article, in which case the form 10 which I will now describe will not be required. I prefer to use a metal form although this form may, if desired, be made of wood or of some other substance. The form which I have used is made of sheet brass, and which is plated with silver or nickel, so that the brass will not be attacked by the wax which I employ, which would stain the finished product.

The form 10 is shown in Fig. 1. This form 10, of brass, plated with silver or nickel, is coated with a very thin layer of bees-wax 11 dissolved in turpentine, the form 10, covered with the bees-wax 11 being shown in Fig. 2 of the drawings. After the bees-wax has hardened on the form, said form is covered with a fibrous material 12. I prefer to use a thin cloth, such as voile, which is stretched over the form with a smooth surface, and without any wrinkles or other blemishes. The fibrous material or voile may be held over the form in any suitable manner.

After the fibrous material or voile has been stretched over the form, the fibrous material or voile is impregnated and stiffened with a substance that will dry without dissolving the bees-wax. I prefer to use gum arabic 13 dissolved in water, because of the fact that the bees-wax on the form is not soluble, and will not be attacked in the said solution of gum arabic 13. When the gum arabic has been applied, it is permitted to dry on the fibrous material or voile, after which several coats of varnish or shellac 14 are applied to the fibrous material or voile impregnated with the gum arabic. The several coats of varnish or shellac tend to harden and thicken the article in course of manufacture. Varnish or shellac is employed because of the fact that the solvent used in varnishes and shellacs will not dissolve the gum arabic, with which the fibrous material or voile has been impregnated.

As has been stated, Fig. 3 shows the fibrous material or voile stretched over the form coated with bees-wax, and Fig. 4 shows the fibrous material after it has been impregnated with the gum arabic. Fig. 5 shows the article in course of manufacture on the form after the several coats of shell-

lac or varnish have been applied. When the varnish or shellac has thoroughly dried another layer of fibrous material or voile 15 is stretched over the article, on the form in course of manufacture. The threads of the second fibrous material or voile 15 are preferably disposed at an angle with reference to the threads of the first fibrous material or voile. This will be seen by comparing

10 Fig. 6, showing the article in course of manufacture on the form, with the second fibrous material or voile applied, with Fig. 3 showing the first layer of fibrous material or voile.

15 By disposing the threads of the second fibrous material or voile at an angle to the threads of the first fibrous material or voile, the article is strengthened considerably, and not only is this the case, but this 20 arrangement of the threads of the fibrous material or voile gives a pleasing effect when the manufacture has been completed and the article is held to the light.

When the second fibrous material or voile 25 has been stretched over the shellac or varnish so that there are no wrinkles or blemishes, it is held in place by any suitable means, and this second layer of fibrous material or voile is impregnated with gum arabic, which is permitted to dry thoroughly. This gum arabic adheres to the varnish or shellac, as it readily passes through the open weave in the fibrous material or voile.

25 When the second layer of gum arabic has thoroughly dried, several coats of varnish or shellac are applied, which is permitted to dry. It will be understood that while I have described the manufacture of an article with only two layers of fibrous material 40 or voile, that any desired number of layers of fibrous material or voile may be used in the manner which has been described with reference to the two layers which are usually employed when the article in course of

45 manufacture is to be twelve inches or less in diameter. When articles of a greater diameter are used, I prefer to employ at least three layers of fibrous material or voile, which are applied and are impregnated with gum arabic and are coated with varnish or shellac in the manner set forth above.

When the article has thoroughly dried, it is customary to coat it with a translucent 55 enamel which serves to give the effect of an egg-shell coating. White translucent enamel may be employed, but it will be understood that translucent enamel having colors may also be employed as occasion may require. When the enamel has dried, the article is removed from the form, which is done by heating the form slightly, thereby melting the bees-wax. This permits the article to be readily removed from the form.

60 65 As has been stated voile is preferably used

in the construction of the shade or bowl and as voile is a very thin, woven fabric it may be stretched smoothly over the form 10, it being possible to pull the web and weft of the voile out of their normal positions to obtain this result.

The gums used form the body of the shade or bowl, the voile which is too thin for this purpose serving as a reinforcing means.

While the term "voile" is used, other very thin fabrics may be employed.

It will be understood that the edge of the article may be trimmed as may be desired. When this has been done, I customarily sew a wire 18 around the edge of the article as shown in Figs. 7 and 8, which gives the article a metallic stiffener. The stitches holding the wire 18 are shown at 17.

It will be understood that the gum arabic which acts as a filler is dissolved in water, and not in alcohol or in oil, and that the shellac is soluble in alcohol, and not in water, and other gums of which varnish is made are soluble in oils, but are not soluble in alcohol or in water. Therefore, there is no danger of the shellac or varnish softening the gum arabic acting as a filler, and with which the fibrous material or voile has been impregnated, and there is also no danger that the second application of gum arabic will soften the varnish or shellac which has been used to cover the first fibrous material or voile.

When the manufacture of the article has been completed, as set forth above, the article may be decorated in any suitable manner.

As the shade or bowl is preferably manufactured, all the materials used are translucent, for a fibrous material, such as voile, is not heavy enough or with a weave close enough to be opaque, and the gum arabic, shellac or varnish, and the enamel are translucent.

When a flat article is manufactured by the method set forth above, the fibrous material is stretched flat by any suitable means when it is impregnated with gum arabic dissolved in water and the other steps of the method are carried out as stated.

Having thus described my invention what I claim as new and desire to secure by Letters Patent is:

1. A method of manufacturing translucent bowls or shades consisting of stretching the web and weft of a thin reinforcing woven fabric out of their normal positions over a curved surface, impregnating and thickening the fabric with a filler, coating the fabric with an adhesive, stretching the web and weft of a second, thin reinforcing woven fabric out of their normal position over the first fabric and impregnating and thickening the second fabric with a filler, the filler and the adhesive forming the body 125 130 135

of the bowl or shade and a fabric forming the reinforcing means.

2. A method of manufacturing bowls and shades consisting of impregnating and stiffening a layer of fibrous material with a filler, coating the layer of fibrous material with a hardening and thickening substance in solution, permitting the hardening and thickening substance to dry on the stiffened fibrous material, applying a second layer of fibrous material, applying a filler to the second layer of fibrous material, coating the second layer of fibrous material with a hardening and thickening substance in solution and permitting the hardening and thickening substance to dry on the second layer of fibrous material, the filler being insoluble in the said solutions.

3. A method of manufacturing translucent bowls or shades consisting of stretching a layer of woven material smoothly over a convex surface, impregnating the material with a filler, coating the material with a hardening and thickening substance, stretching a second layer of woven material smoothly over the first layer of woven material with the web and weft of the second material at angles to the web and weft of the first material and impregnating the second layer of material with a filler.

4. A method of manufacturing translucent bowls or shades consisting of stretching a layer of thin woven reinforcing material smoothly over a convex surface, impregnating the material with a filler and coating the material with a hardening and thickening substance, the filler and the hardening and thickening substance forming the body of the shade or bowl which is reinforced by the woven material.

5. A method of manufacturing bowls and shades, consisting of impregnating and stiffening a layer of fibrous material with a gum applied in a solvent, drying the gum, coating the fibrous material with a different gum applied in a solvent different from the first mentioned solvent, applying a second layer of fibrous material, impregnating and stiffening the second layer of fibrous material with the first mentioned gum and solvent, and coating the second layer of fibrous material with the second mentioned gum and solvent, the first mentioned gum being insoluble in the second mentioned solvent.

6. A method of manufacturing bowls and shades, consisting of impregnating and stiffening a layer of fibrous material with a gum applied in a solvent, drying the gum, coating the fibrous material with a different gum applied in a solvent different from the first mentioned solvent, applying a second layer of fibrous material, impregnating and stiffening the second layer of fibrous material with the first mentioned gum and

solvent, coating the second layer of fibrous material with the second mentioned gum and solvent, and the application of an enamel, the first mentioned gum being insoluble in the second mentioned solvent.

7. A method of manufacturing bowls and shades, consisting of spreading a layer of fibrous material over a mold, the application of gum arabic dissolved in water to the fibrous material for stiffening purposes, and the application of a varnish on the fibrous material.

8. A method of manufacturing bowls and shades, consisting of spreading a layer of fibrous material over a mold, the application of gum arabic dissolved in water to the fibrous material for stiffening purposes, the application of a varnish on the fibrous material, and the application of a translucent enamel over the varnish.

9. A method of manufacturing bowls and shades, consisting of coating a form with a layer of bees-wax dissolved in turpentine, spreading a layer of fibrous material over the bees-wax, the application of a gum to the fibrous material for stiffening purposes, the application of a gum at the outer side of the fibrous material for thickening the article which is in course of manufacture, and heating the form slightly to melt the bees-wax, and free the manufactured article from the form.

10. A method of manufacturing bowls and shades, consisting of coating a form with a layer of bees-wax dissolved in turpentine, spreading a layer of fibrous material over the bees-wax, the application of a gum to the fibrous material for stiffening purposes, the application of a gum at the outer side of the fibrous material for thickening the article which is in course of manufacture, heating the form slightly to melt the bees-wax and free the manufactured article from the form, and securing a wire around the edge of the bowl or shade.

11. A method of manufacturing bowls or shades consisting of stretching a layer of thin, meshed, reinforcing fabric smoothly over a convex surface, impregnating the fabric with a filler, coating the fabric with a hardening and thickening substance, stretching a second layer of thin, meshed reinforcing fabric over the first layer of fabric and impregnating the second layer of fabric with a filler.

12. In a shade or bowl, gum forming the body of the shade or bowl which is reinforced by layers of thin curved fibrous material to stiffen and hold the gum in position.

13. In a shade or bowl, two curved layers of fibrous material which are spaced apart by the gum which serves to bind the layers of fibrous material relatively to each other, the threads of one layer of fibrous

material being disposed at angles with reference to the threads of the other layer of fibrous material.

14. In a translucent shade or bowl a plurality of curved layers of reinforcing fibrous material and translucent means forming the body of the shade or bowl which stiffen and hold the layers of fibrous material relatively to each other.

10 15. In a shade or bowl a plurality of curved layers of fibrous material spaced apart, each impregnated and stiffened with a translucent material and another translucent material which binds the curved layers 15 of fibrous material in position relatively to each other.

16. A method of manufacturing shades, consisting of coating a form with a layer of matter which will be softened by heat, the 20 manufacture of the shade on the said form and the heating of the form to soften the said matter and free the shade from the form.

17. A method of manufacturing bowls or

shades consisting of stretching a layer of 25 fibrous material smoothly over a curved surface, impregnating the fibrous material with a filler, coating the fibrous material and the filler with a hardening and thickening substance in solution, and permitting 30 the hardening and thickening substance to dry, the filler being insoluble in the solution.

18. A method of manufacturing bowls or shades consisting of spreading a layer of 35 fibrous material over a mold, impregnating and thickening the fibrous material with a filler, coating the fibrous material with an adhesive, spreading another layer of fibrous material over the first layer of fibrous material and impregnating and thickening the 40 second layer of fibrous material with a filler.

19. In a shade or bowl a plurality of layers of voile, each impregnated and stiffened with a filler and an adhesive between the 45 layers of voile which binds the layers of voile together at all parts.

ARTHUR JAMES TIZLEY.
